UNITED STATES PATENT OFFICE.

ALBERT J. BROWN AND JOHN J. DAVIES, JR., OF PHILADELPHIA, PENNSYLVANIA.

DRY DOCK.

1,410,243.

Specification of Letters Patent. Patented Mar. 21, 1922.

Application filed July 7, 1920. Serial No. 394,562.

To all whom it may concern:

Be it known that we, ALBERT J. BROWN and JOHN J. DAVIES, Jr., citizens of the United States, residing at Philadelphia, 5 county of Philadelphia, and State of Pennsylvania, have invented certain new and useful Improvements in Dry-Docks, of which the following is a specification.

One object of our invention is to provide 10 an improved drydock which can be operated by fluid pressure, such as hydraulic or water pressure, to raise a boat bodily from the water to the necessary height to enable repairs to be conveniently made below its water 15 line.

Another object is to so construct the dock of our invention that it will be of a strong practical character.

These objects, and other advantageous ends 20 which will be described hereinafter, we attain in the following manner, reference being had to the accompanying drawings in which

Figure 1 is a top plan view of our improved dock,

Figure 2 is an end elevation, partly in section, and showing our improved dock in an inoperative position ready to raise a boat,

Figure 3 is an end elevation showing the boat having been raised,

Figure 4 is an enlarged fragmentary elevation, partly in section, showing certain of the features of our invention,

Figure 5 is a section taken on the line 5-5 of Figure 4, and

Figure 6 is a fragmentary view showing a modified form of certain of the features shown in Figure 4.

Referring to the drawings, the dock 7 is 40 constructed of a structural steel frame work 8 including transversely extending girders 9. These girders are spaced apart throughout the length of the frame work and are 45 supported by solid steel plungers 10 which fit within hydraulic pipe casings 11; said casings resting upon a concrete foundation 12 and being tied together by structural steel bracing 13. As illustrated each of the

50 girders 9 has two plungers 10 depending therefrom into respective casings 11 and the bottoms of the casings 11 are connected together by longitudinally extending headers or manifolds 14; the manifolds being joined 55 by transversely extending nipples 15. The dock 7 is positioned between longitudinally

extending side walls 16; said side walls being preferably made of a concrete construction and towering to the entire height of the dock when the latter is in its elevated position. The dock 7 is adapted to slide upwardly and downwardly between steel rails 17 which are anchored in the concrete wall 16 at spaced distances apart; the sides of the dock having rail guides 18 slidably embracing the rails 17 as clearly shown in Figures 1, 2 and 3. Housings 19 are supported at each side of the dock upon the girders 9 and have inner opposed surfaces 20 which curve downwardly to a keel supporting member 70 21 which extends longitudinally of the dock and is provided with a central groove 22.

Conduits 23 in the form of pipes, telescopically slide at their lower end portions within pipe casings 24; said pipe casings 24 75 being secured below the girders 9 to the concrete foundation by being strapped or otherwise held to the side walls 9. The upper ends of the conduits 23 extend within the housings 19 and have branches 25 extending laterally 80 therefrom in the form of plunger casings which slant slightly upward as clearly shown in Figures 2, 3 and 4. Laterally extending plunger arms 26 slidably extend through the curved surfaces 20 of the housings 19 into 85 the plunger casings 25; said plunger arms having pressure plates 27 adapted to be moved into engagement with the outer surface of the hull of the boat as illustrated in Figure 3. As illustrated each of the housings contains three plunger casings 25 arranged at different levels; each of said casings 25 having a laterally extending plunger arm 26 slidable therein so that said pressure plates will engage the outer surface of the 90 hull at different levels. Each of the plunger casings 25 includes a gate valve 28 having a by-pass valve 29 in connection therewith for a purpose hereinafter described.

The lower ends of the pipe casings 24 connect with longitudinally extending headers 30 and the headers 30 are connected by nipples or transversely extending pipes 31.

A main feed pipe 32 which may lead from 105 accumulator tanks for containing the pressure fluid leads downwardly at the extreme water end of the dock to the bottom where it joins with one of the headers 14; said main feed pipe including a hydraulically operated gate valve 33 and a safety check 110 valve 34; said check valve being positioned between the hydraulically operated gate

valve and the accumulator tank; said accumulator tank not being illustrated in the drawings. The hydraulically operated gate valve 33 which may be of any desirable type 5 also includes a by-pass valve 35 which may be open under certain conditions hereinafter described. In similar manner an auxiliary feed pipe 36 leads from said accumulator tanks and communicates with one 10 of the headers 30; said auxiliary pipe 36 including a hydraulically operated gate valve 37 and a by-pass valve 38. A boat, such as the boat illustrated at 39, which is docked and raised out of the water for the purpose 15 of repairing the same, can be moved in between the walls 16 as shown in Figure 3 so as to be positioned over the cradle or space between the curved surfaces 20 of the housings 19. Pressure fluid is admitted into the 20 casings 11 by operating the valve 33 and the pressure fluid will serve to raise the plungers 10 and consequently the dock between the side walls 16. When the dock reaches a height so that the keel of the boat will 25 engage within the groove 22 of the keel supporting member 21, the tops of the housings 19 will be in a position out of the water and if desired the valves 28 can be opened to cause the pressure fluid which is admitted 30 through the valve 37 to move the plunger arms 26 so that the plates 27 will engage the outer side surfaces of the boat 39. A continued upward movement of the dock will then lift the boat completely out of the 35 water as clearly shown in Figure 3 and any necessary repairs may be made.

If it is desired any one of the plunger arms can be released by closing the respective valve 28 and opening the by-pass valve 40 29 to permit escape of the pressure fluid between the valve 28 and said plunger arm 26. The latter will then slide inwardly and in this manner the various plunger arms can be controlled from time to time if the 45 repair necessitates that certain of the arms 26 must be moved away from the hull 27.

When it is desired to again lower the boat into the water the various by-pass valves 29 can be opened as can also the by-pass valves 50 35 and 38 and the dock will gradually descend until the boat floats in the water.

The check valves 34 merely act as safety means against back pressure and the dock may be supported in its raised position for 55 any desired time. It will be noted that the plunger casings 25 telescopically slide within but always keep in communication with the pressure fluid in the pipe casings 24.

If it is desired instead of making the 60 pressure plates 27 integral with the plunger arms 26 they may be made with a knuckle connection and in Figure 6 I have illustrated the pressure plates at 27^a in

knuckle connection with the plunger arms 26^a so that if there is any slight movement 65 necessary in order that the pressure plates properly contact with the side of the boat, these plates 27^a can slightly move to the limit prescribed by the knuckle connection.

While we have described our invention 70 as taking a particular form, it will be understood that the various parts of our invention may be changed without departing from the spirit thereof, and hence we do not limit ourselves to the precise construction 75 set forth, but consider that we are at liberty to make such changes and alterations as fairly come within the scope of the appended claims.

Having thus described our invention, 80 what we claim as new and desire to secure by Letters Patent is:—

1. A dock having a portion adapted to serve as a support for a boat, said dock being movable upwardly and downwardly; laterally arranged plunger casings on said dock; a supporting structure; plunger arms in said casings; a conduit for pressure fluid, said conduit being made in telescopically 85 slideable sections secured respectively to the supporting structure and to the dock, the section which is secured to the dock being in communication with said plunger casings; and means for supplying pressure fluid to the section which is secured to said 90 supporting structure whereby pressure fluid can be supplied to said plunger casings, to move said arms, irrespective of the position of said dock; substantially as described.

2. A dock having a portion providing a 100 cradle formed by housings which are opposed to each other, said dock being movable upwardly and downwardly; laterally arranged plunger casings within said housings; a supporting structure; plunger arms 105 in said casings; a conduit for pressure fluid; said conduit being made in telescopically slideable sections secured respectively to the supporting structure and to the dock, the section which is secured to the dock being in communication with said plunger casings; and means for supplying pressure fluid to the section which is secured to the supporting structure whereby pressure fluid can be supplied to said plunger casings, to move 110 said arms, irrespective of the position of said dock; substantially as described.

In testimony whereof we have signed our names to this specification in the presence of two subscribing witnesses.

ALBERT J. BROWN.
JOHN J. DAVIES, JR.
